UNITED STATES PATENT OFFICE

HARRY L. MEAD, OF BREWSTER, FLORIDA, ASSIGNOR TO AMERICAN CYANAMID COMPANY, OF NEW YORK, N. Y., A CORPORATION OF MAINE

SYSTEM AND METHOD OF HYDRAULIC MINING

Application filed September 15, 1924. Serial No. 737,721.

This invention relates to mining, more particularly to an improved system and method of hydraulic mining.

Hydraulic mining is generally carried out by directing a stream of water under high pressure against the face of a cliff or bank which is to be mined, the stream of water first dislodging the material and then carrying the same to a sump or well from which it may be transported to other points for further treatment. Generally the mixture of water and material is elevated by a pumping system to the ground level where it passes thru various devices for purification, concentration, grading, sizing and washing.

Water under high pressure is directed against the face of the bank by means of a nozzle. This water, however, tears down more rock than it can carry away, the result being that the operator must intermittently divert the stream of high pressure water from the face of the cut and utilize the water to carry the rock and débris back to the sump, from which it may be pumped to wherever needed. This is an expensive operation because high pressure water is used for an operation which may be carried out by low pressure water.

My invention is adapted to obviate the disadvantages of the prior system, it being among the objects thereof to devise an improved system of hydraulic mining which shall be simple in construction, easy to operate and have an increased efficiency over the systems of the prior art.

Mining efficiency is largely dependent upon the percentage of solids in the mixtures which are put thru the mining pumps. It is well known that a mixture of 50% solids and 50% water may be pumped using standard mining equipment. The problem has been, however, to get the mined material to the sump in sufficient quantities to yield such a mixture. When a new sump is started, on account of short ditches and steep grades it is often possible to approach the limit, but after the bank has receded a distance of over fifty feet from the sump the flatness of the grade of the ditches so reduces the transporting power of the water that not more than 25% solids exist

in the mixture in the well. By means of my present invention, I have found that I can increase the percentage of solids to 40.

In practicing my invention, I provide a source of high pressure water and a pumping system whereby material may be loosened from the face of the rock and afterwards elevated to the auxiliary treating apparatus. In the pumping system I provide a device for extracting water freed from particles of material and return at least part of the same to the face of the bank to be mined to assist the high pressure water in transporting the material to the sump.

In the accompanying drawing, the single figure is a diagrammatic vertical, sectional view of a phosphate mine showing my improved system in place.

The mine consists essentially of bed rock 1 upon which is found the valuable phosphate rock 2 to be mined. Generally the rock is covered by an overburden 3, the surface 4 of which is the level of the ground. Below the level of the rock 2 is a well or sump 5 in which a mixture of material and water is allowed to accumulate. In mining the rock, the overburden is stripped off exposing the surface 6 of the phosphate rock 2. A source 7 of high pressure water terminates in a nozzle 8 which is directed against face 9 of the rock 2 whereby material is dislodged, some of it being carried into the sump 5 and a portion of it accumulating at the base of the rock in a mass 10.

A pipe 11 dips into the liquid mixture 12 in the sump 5 and communicates with the inlet of a centrifugal pump 13, the outlet of which directs the stream thru the line 14 to other apparatus for further treatment. A de-watering device 15 in the line 14 has an outlet pipe 16 terminating in a nozzle 17. A suitable regulating valve 18 is placed in the last named pipe line. The de-watering device 15 consists merely in an enlarged chamber the diameter of which is several times that of the pipe 14.

The operation of my device is as follows:

Water from high pressure nozzle 8 is directed against the face 9 of the rock causing material to be dislodged therefrom and to be

carried into the sump 5. Low pressure pump 13 removes the mixture therefrom, some of the water being removed by the de-watering device 15 and passed thru pipe 16 at a pressure lower than that of nozzle 8 to the nozzle 17, which is directed against the material 10 which has accumulated at the base of the rock, thereby carrying it into the sump. Valve 18 may be regulated to vary the amount of water returned to the nozzle 17 in accordance with the amount of material 10 which has accumulated.

Assume that water is applied to the face of the phosphate rock thru the high pressure nozzle at 140 pounds nozzle pressure and at the rate of 2600 gallons per minute. If I operate the device so as to return 800 gallons of water per minute at 50 pounds nozzle pressure to the face of the phosphate rock, I have found that this returned water together with that from the high pressure nozzle will be sufficient to carry to the sump all the solids that the high pressure water tears down. Thus I am relieved of the necessity of using all high pressure water for transporting solids previously dislodged.

When the system is in equilibrium, in the above cited example, 2600 gallons per minute from the nozzle and 800 gallons of return water from the de-waterer will be flowing into the sump, a total of 3400 gallons of mining water. The discharge from the de-waterer will be carrying away 2600 gallons of mining water per minute and this 2600 gallons will carry thru pipe 14 all the solids brought to the sump by the 3400 gallons. Thus I have increased the efficiency of transportation of rock in the ratio of eight to twenty-six or approximately 32%. That is, if the amount of solids in the water entering the well is 25% the amount leaving the de-waterer thru pipe 14 will be approximately 33%.

My improved system has many advantages over systems previously in use. I merely add to the apparatus a de-watering device and a valve controlled pipe and nozzle. The entire system is simple to operate and requires very little additional power, which may be measured by the small difference between the level of the nozzle 17 and the surface of the material 12 in the sump. By this means, I obtain a large increase in the percentage of solids carried out of the mine. I may vary the amount of water returned to the system to suit the conditions of mining; for instance, if the distance between the rock 2 and the sump 5 is greater or smaller I may return more or less water thereto thru pipe 16 by a regulation of the valve 18, to carry into the sump the material 10, the amount of which is roughly proportional to the distance of the face 9 of the rock from the sump 5.

What I claim is:

1. In a system of hydraulic mining,

sump, a high pressure nozzle for directing material to said sump, a pump system for removing material from said sump, a de-watering device in the pump system, and means for utilizing water from said pump system for directing material into said sump.

70

2. In a system of hydraulic mining, a sump, a high pressure nozzle for directing material to said sump, a pump system for removing material from said sump, a de-watering device in the pump system, means for utilizing water from said pump system for directing material into said sump and means for regulating the amount of water so utilized.

75

3. In a system of hydraulic mining, a sump, a high pressure nozzle for directing material to said sump, a pump system for removing material from said sump, a de-watering device in the pump system, means for utilizing water from said pump system for directing material into said sump, the amount of water so utilized being at least 20% of the water issuing from the high pressure nozzle.

80

4. A system of hydraulic mining comprising a pump system for causing a mixture of material and water to flow into a sump, means for pumping said mixture to a remote point, means for reducing the velocity of flow at an intermediate point to cause a partial separation of water and material, means for conveying the separated material to said remote point and means for conveying the separated water for further use under the pressure of the pump.

85

5. A method of hydraulic mining consisting of excavating material by a stream of high velocity, conveying said material by a stream of lower velocity into a sump, discharging the mixture of material and water through an apparatus by which a portion of the water is removed, while still being kept under pressure, and then utilizing said portion as part of said mentioned stream of low velocity.

90

6. A method of hydraulic mining which comprises directing a stream of water against the material to be mined, the said stream being sufficient to dislodge more material than can be carried away thereby and directing another stream to carry away such material, said second stream being derived from the mixture of material and water being carried away and being under less pressure.

95

7. A method of hydraulic mining which comprises directing a stream of water against the material to be mined, said stream being sufficient to dislodge more material than can be carried away thereby, causing the stream to flow into a sump, pumping a mixture of water and material from the sump and returning part of the water so pumped under pressure of the system to carry material into the sump.

130

8. In a system of hydraulic mining, a sump, a high pressure nozzle, and a low pressure nozzle supplied with fluid from the mixture being pumped from said sump, for directing material to said sump.
- 5 9. In a system of hydraulic mining, a sump, a high pressure nozzle, and a low pressure nozzle supplied with fluid from the mixture being pumped from said sump, for directing material to said sump, the pressure of the streams issuing from the nozzles being above and below 100 lbs. per sq. in. respectively.
- 10 10. In a system of hydraulic mining, a sump, a high pressure nozzle, and a low pressure nozzle supplied with fluid from the mixture being pumped from said sump, for directing material to said sump, the pressure of the streams issuing from said nozzles being about 140 and 50 lbs. per sq. in. respectively.
- 15 11. In a system of hydraulic mining, a sump, a high pressure nozzle, and a low pressure nozzle supplied with fluid from the mixture being pumped from said sump, for directing material to said sump, the pressure of the streams issuing from said nozzles being about 140 and 50 lbs. per sq. in. respectively, and the ratio of the amounts of water being about 26 to 8.
- 20 30 In testimony whereof, I have hereunto subscribed my name this tenth day of September, 1924.

HARRY L. MEAD.
